Patented Apr. 16, 1918.

UNITED STATES PATENT OFFICE.

JOHN ARTHUR BRANDT, OF ST. LOUIS, MISSOURI.

RECEIVED AND FILED APRIL 16, 1918.

MARKING MACHINE.

1,263,198.

Specification of Letters Patent.

Patented Apr. 16, 1918.

Application filed March 3, 1917. Serial No. 152,375.

To all whom it may concern:

Be it known that I, JOHN ARTHUR BRANDT, a citizen of the United States, and resident of St. Louis, Missouri, have invented certain new and useful Improvements in Marking-Machines, of which the following is a specification containing a full, clear, and exact description, reference being had to the accompanying drawings, forming a part 10 hereof.

My invention relates to improvements in marking machines especially ground marking devices such as are used for marking tennis courts, etc.

15 The object of my invention is to devise a simple practical marker, one which is simple to manipulate, and which facilitates the drawing of a straight line; one which prevents the useless spreading of the coloring matter and makes a clearly defined line, and one that will not cut into the ground or court unnecessarily.

I have illustrated a dry marker, but do not wish to be limited to it as my construction is equally well adapted with a wet marker. In a dry marker, a powder is used for the coloring matter and in a wet marker, a viscous liquid is utilized.

20 In the conventional marker, a hollow cylinder is mounted on a shaft passing through its geometrical center; the handle is rotatively secured to the shaft. The convex lateral surface is perforated, so that when the cylinder is filled with a coloring powder (usually pulverized lime) and rolled along the ground or earth, the powder is precipitated on to the ground, thereby forming a streak over the cylinder path. It is desirable to have a clearly defined line of the 25 width of the convex lateral cylinder surface, but owing to the fact that the powder is always sifting through at least one half of the cylinder, the powder has quite a distance to fall *i. e.*, the diameter of the cylinder. The cylinder must be made reasonably large to be the container for a considerable amount of the powder to prevent frequent refillings. The minimum reasonable diameters of such cylinders approximates one foot. The powder being fine spreads and forms a streak instead of the required line.

In order to mark a straight line of any considerable length, great precision, and

steady nerves are required, owing to the limited point of contact between the cylinder and the ground.

My device obviates all these difficulties. With the above and other objects in view, my invention has relation to certain novel features of construction and operation, examples of which are described in the following specification and illustrated in the accompanying drawings, in which,

Figure 1 is a front elevation of my device.

Fig. 2 is a transverse sectional elevation of Fig. 1.

Fig. 3 is an enlarged detail plan of the powder opening.

Fig. 4 is an enlarged elevation of the scoop entrance to the powder chamber.

Fig. 5 is a plan view of the device shown in Fig. 4.

In the drawings, numeral 6 designates a powder magazine formed of three principal parts viz., the sides 7 and the annulus 8. The annulus 8 is perforated as at 9. The sides 7 and the annulus 8 are fitted together by means of the annular grooves 10 formed at 75 the periphery of the sides 7. 11 designates a hole in the geometrical center of the powder magazine in which is positioned a bolt 12 having threads 13 on both extremities. The sides 7 are countersunk at 14 to permit 80 the entrance of the nuts 15 which are screwed on to the bolt 13 as shown by Fig. 2. By tightening the nuts 15 on the bolt 12 in the countersunk portions 14 of the sides 7, the sides 7 are tightened on to the annulus 8. Mounted rotatively on the bolt 12, exteriorly adjacent the nuts 15, is the guard 16. The washers 17 are then placed on the bolt 12 and then the prongs 18 are rotatively secured to the bolt 12 exteriorly to the 90 washer 17. The pins 19 piercing the bolt 12 near its extremities prevents the prongs from disengaging the bolt 12. The prongs 18 are firmly secured to the handle 20 by means of the bolts and nuts 21. The guard 100 16 is inclosed front and rear as shown by the overturned edges 22 in Fig. 1 of the inclosing element. The guard 16 is fastened to the bolt 12 by means of the slot 23. By means of this slot relative vertical movement of the guard and the powder magazine is made possible. The front and rear ends of the guard are curved so as not to

105

present sharp corners to possible obstacles with which the guard may come in contact when in use, but rather rounded edges to permit the guard to ride over the obstacle. 5 The guard 16, near its lower edge has formed the corrugation 24 for the purpose of preventing the guard from sinking too deeply into the ground. Formed in one of the sides 7, is the hole 25 through 10 which the powder is placed in the magazine. The cover 26 for this opening 25 consists of a scoop as shown in Figs. 4 and 5, with the lid portion 27 and the knob 28. The hole 25 has two notches 29 formed in its 15 side for the reception of the two hooks 30. By inserting the cover 26 into the opening 25 so that the hooks 30 will register with the notches 29 and then pushing the cover 26 inwardly, the hooks 30 will be positioned 20 under the edges 31 of the opening 25. By turning the cover 26, the hooks 30 will be placed under the edges 31 and hence the cover 26 will be firmly but detachably secured in the opening 25. This cover and 25 scoop is simple and performs the dual function of a scoop for the powder and a cover for the opening into the magazine. Owing to its structure it cannot become inoperative on account of dirt, etc., as is the case 30 with all the conventional covers now on the market. The operation of my device is as follows.

By a manual application to the handle 20, the marker is moved over the ground to be 35 marked. The guard 16, holds the powder within its narrow confines until the powder reaches the ground, the corrugation 24 preventing the guard from sinking farther into the ground than is desired. Furthermore 40 owing to the large surface now in contact with, and supported by the ground, on ac-

count of the guard 16, a straight line of almost indefinite length can be made.

What I have illustrated and described and mean to secure by Letters Patent is:

1. In combination with a hollow cylindrical powder magazine, having perforations on its periphery, and an opening in its side for the reception of powder, a guard composed of two trapezoidal shaped members 50 spaced apart by supports and having curved ends, for confining the powder within selectable limits, and a shaft, said magazine and guard secured to said shaft, said magazine positioned within said guard. 55

2. In combination with a hollow cylinder having perforations on its lateral convex surface, and means for entrance to said cylinder on its side, a combination scoop, disintegrator and cover for said entrance 60 means, consisting of a cylinder portion with the one extremity sealed by a disk and means for selectively securing said scoop to said means for entrance to said cylinder so that the cylinder portion of said scoop when in 65 position will protrude in said hollow cylinder, a guard enveloping the lower half of said cylinder, with a corrugation formed longitudinally near its lower extremity and its front and rear portions curved, a shaft 70 and a handle, said cylinder, said guard, and said handle secured to said shaft and means for moving said guard vertically relative to said cylinder, substantially for the purposes described. 75

In testimony whereof, I have signed my name to this specification in presence of two subscribing witnesses.

JOHN ARTHUR BRANDT.
